GOLF PUTTER SIGHT

Glen N. Capps, 8 Burnham Place, Newport News, Va.

Filed Mar. 15, 1965, Ser. No. 84,253

Term of patent 14 years

(Cl. D34—5)

The golf putter head seen in broken lines in FIGURE 1 is for illustrative purposes only.

The stippled area appearing in FIGURES 3-5 denote a pressure sensitive material.

I claim:

The ornamental design for a golf putter sight, as shown and described.
